United States Patent Office

Des. 208,550
Patented Sept. 12, 1967

208,550

SEPARABLE ELECTRICAL CONNECTOR HOUSING

William Ludlow Schumacher, Camp Hill, Pa., assignor to
AMP Incorporated, Harrisburg, Pa.

Filed Apr. 21, 1966, Ser. No. 1,970

Term of patent 14 years

(Cl. D26—1)

Des. 208,550

PAGE 2

FIGURE 1 is a perspective exploded view of the separable electrical connector housing;

FIGURE 2 is a perspective view thereof in assembled position;

FIGURE 3 is a side elevational view of FIGURE 2;

FIGURE 4 is an elevational view of the right side of FIGURE 3;

FIGURE 5 is an elevational view of the left side of FIGURE 3;

FIGURE 6 is a top plan view of FIGURE 3; and

FIGURE 7 is a bottom plan view of FIGURE 3.

I claim:

The ornamental design for a separable electrical connector housing, as shown.
